UNITED STATES PATENT OFFICE

DAVID B. BROWN, OF BELLINGHAM, WASHINGTON

STRAIGHT-RAZOR STROPPING MACHINE

Application filed July 23, 1930. Serial No. 469,981.

My invention relates to improvements in straight razor stropping machines.

I was granted Patent Number 1,455,567 for safety razor blade sharpeners on May 15, 5 1923.

This invention has for an object to provide a machine to sharpen the old fashioned or straight razors, sometimes referred to as barber's razors.

10 Another object of improvement is to provide a razor holder suited for retaining the razor while in the machine which will allow the razor back and edge to simultaneously bear on the strop.

15 Another object of my improvement is to provide a razor sharpener adapted to cause the razor edge to alternately bear on opposite sides thereof while being stropped.

Another object of my improvement is to 20 provide a razor sharpener adapted to cause both the razor and the strop to move resulting in a relatively drawing movement between the strop and the razor edge.

Another object of my improvement is to 25 provide a razor sharpening machine suited for individual use to sharpen a razor while the patron is being prepared for shaving.

Other objects of my improvements will appear as the description proceeds.

30 I attain these and other objects of my improvement with the mechanism illustrated in the accompanying two sheets of drawings which form a part of this specification in which Figure 1 is a plan view of my razor sharpener, suited for individual use, in which neither razor holder nor razor is shown, Fig. 2 is a front side elevation of Fig. 1 with a razor holder and razor in place therein, Fig. 3 is a segregated bottom plan view 35 of the pivoted holder carrier and axial oscillator, Fig. 4 is a segregated plan view of the stropping discs with a razor holder and a razor in place therein parts of the holder and razor being broken away. Fig. 5 is a top 40 plan view of the razor holder, Fig. 6 is a front side elevation of the razor holder, Fig. 7 is a segregated edge elevation of the razor blade holder, Fig. 8 is a front elevation of the holder bar, Fig. 9 is a segregated front 45 elevation of the holder carrier partly in sec-

tion on a medial vertical plane and Fig. 10 is a segregated top plan view of the cam and cam gear.

Similar characters refer to similar parts throughout. Certain parts are broken away 55 to show other parts hidden thereby.

With more particular reference to the designated parts: Base 12 has a central opening to accommodate parts of the mechanism and is overlaid with base plate 13 fastened thereto. Bearing brackets 14 and 15 are fastened to the base plate and provide bearings for shaft 16 mounted therein for revolution. Discs 17, 17 are fastened on shaft 16 spaced apart by sleeve 16 and have adjacent 60 their opposite surfaces stropping discs 18, 18 mounted on shaft 16 and retained against discs 17 by flange washers b16, b16. Discs 17 are fastened on shaft 16 to revolve therewith and retained in place by fastening 65 means, not shown, in disc hubs c16, c16.

Sheave 55 is fastened on the rear end of shaft 16. The shaft of electric motor 56 is parallel with shaft 16 and has drive sheave 57 fastened on the end thereof in belting relation with sheave 55 and over these two 70 sheaves is placed belt 58 for a power driving connection.

Spur gear 23 is fastened on the front end of shaft 16 adjacent and to the rear of 75 bracket 14 to revolve with the shaft.

A cam-driven frame has bottom horizontal member 24 and vertical rectangular frame a24 providing rectangular opening 27 in which operates cam 21. Cam 21 is on the rear surface of and is integral with spur gear 19 which has gudgeon 20 centrally located thereon and is mounted thereon in a bearing in bracket 14 for revolution disposed to engage with spur pinion 23 and is driven thereby. On cam 21 is crank pin 22 extended rearward and best shown in Fig. 10. Frame member 24 has a dependent projection 26 extended through opening a13 in the base plate to which is fastened plate 25 disposed horizontally beneath base plate 13 adjacent thereto to cooperating with member 24 in using the base plate as a guide for frame 24, a24 to direct its horizontal reciprocations.

80 A carrier for the razor holder has recum- 100

bent bar 28 to the right hand end of which is joined hollow post 29. A pair of lugs 30 is fastened to the base plate beneath motor 20 between which is mounted the left-hand end 5 of bar 28 and to which it is pivoted by pin a_{31} extended through registering holes in the lugs and hole 31 in the bar to dispose post 29 between plates 17, 17 at the left of shaft 16.

Standard 32 is fastened to bar 30 and to its 10 upper end is fastened horizontal arm 33 having horizontal slot 34 therein engaged with crank pin 22 on the cam. The construction providing for the horizontal reciprocation of frame 24— a_{24} by the revolution of cam 21 15 and the oscillation of post 29 by the revolution of crank pin 22 all of which is caused by the revolution of gear 23.

Hollow post 29 mounts hollow shaft 35 for oscillation. On the upper end of shaft 35 is 20 head 36 having upwardly extending lug 37 and near the lower end of the shaft is fastened collar 38 which together with head 36 retains shaft 35 in post 29. On the lower end of shaft 35 is fastened arm 39 which on its 25 outer end mounts a pair of spring arms 40, 40, which are pivoted to arm 39 by bolt 41 extended through registering holes in the spring arms and hole a_{39} in arm 39 and also through intervening washers b_{39} , b_{39} to offset the springs from arm 39. The construction 30 provides for the oscillation of spring arms 40, 40 with shaft 35 and the freedom of oscillation of the springs on bolt 41. Spring arms 40, 40 are disposed to have their ends 35 extended through openings a_{25} , a_{25} in plate 25. The construction provides for the oscillation of shaft 35 by the reciprocation of plate 25. Since shaft 35 also oscillates vertically with post 29 and the ends of spring 40 arms 40, being engaged in holes a_{25} which have no vertical movement, can not follow the vertical oscillations of bolt 41 their pivotal engagement with this bolt provides for the required vertical oscillations of the pivoted ends of the springs. 45

Razor holder block 42 has rod 43 fastened in its lower end and bolt 45 engaged in a tapped hole in its upper end. Bolt 45 has head a_{45} thereon and rod 43 has terminal rod 50 44 pivoted to its lower end. Rods 43 and 44 are adapted to be extended in hollow shaft 35 when the lower end of block 42 bears on the upper end of head 36 and lug 37 thereon 55 engages with notch b_{42} in the lower end of block 42 to cause said block to engage with head 36 for radial oscillation therewith.

Razor holder back bar 46 is bent at right angles at 47 and to the bent end is fastened spring 48 offset therefrom, adapted to retain 60 the shank of a straight razor therebetween. A pair of springs 50, 50 fastened in head block 49 are suited to engage the end of a razor blade therebetween. To head 49 is fastened threaded shank 51 which is engaged in 65 a tapped hole in the lower end of bar 46.

Razor blade rest 52 has a threaded shank 53 to engage in a tapped hole in bar 46 above head 49 and serves to bear against the back of a razor blade when the end thereof is engaged between springs 50, 50. The threaded shanks of head 49 and rest 52 provide for adjustments to accommodate razor blades of different widths. Threaded shank 54 extends at right angles from the back of bar 46 70 to which it is fastened and is engageable in threaded hole a_{42} in block 42. It is preferred that the engagement between shank 54 and block 42 be easy so that the shank may easily oscillate in the block for reasons to be referred to. With shank 54 engaged in block 42 and rod 43, 44 extended into hole a_{35} in hollow shaft 35 and block 42 bearing on shaft head 36 with the block engaged by lug 37 the razor holder is ready to receive a straight razor such as the one shown having blade A, 85 shank B and handle C. For conveniently placing the razor in the holder the latter is withdrawn and placed on motor 20 with block 42 at 42' bearing on bracket 54 fastened to the motor, as shown in dotted outline in Fig. 1, while the articulate rod end 44 of the holder rod remains in shaft 35 at 44'. Then the several designated parts of the holder are in their positions indicated by the primes of their designating characters. The razor handle C is turned back and shank B thereof is inserted between the end of spring 48 and bar 47 while the end of blade A is introduced between springs 50, 50 and the back of the razor blade at the end thereof is caused to bear on rest 52 when the razor is in proper place in the holder for sharpening. Now the holder with the razor is set upright with the razor between leather discs 18, 18 and rod 43 90 extended into shaft 35 and block 42 bearing on and engaged with shaft head 36, while handle C bears on bolt head 45 and is supported thereby. 95

The motor is started causing all of the movable parts of the sharpener to operate. 110 Discs 17 and leather discs 18 revolve in the direction indicated by the arrow in Fig. 1, razor blade A is caused to oscillate longitudinally in an arc about pin a_{31} while it oscillates transversely about the axis of shaft 35 115 to contact alternately with leather discs 18, 18, where the blade including the edge thereof is caused to bear flatwise against the leather which is moving from the back over the edge thereof. 120

In the segregated plan view in Fig. 4 the razor blade is shown in section on line 4—4 of Fig. 6 and the dotted lines indicate the movement thereof and location against the opposite leather disc 18. It is evidently desirable that the force causing the razor blade to bear on the leather should be flexible. This is attained by resilient arms 40, 40 attached to the lower end of shaft 35 which convey power from reciprocating plate 25 to shaft 130

35. The "drawing" character of the stropping stroke so desirable in sharpening a razor is provided by the longitudinal oscillation of post 29. In changing from disc to disc the 5 blade should be free to bear flatwise throughout its length against the discs. This is attained by the free turning shank 54 in block 42.

Adjustments are provided for by threaded 10 shanks 51, 53 and 54 as well as by threaded bolt 45.

When sharpening of the razor is complete, current is turned off of the motor, allowing the machine to stop, and the holder is withdrawn 15 to again lie on bracket 54 when the razor may be conveniently removed from the holder.

In the drawings dotted lines indicate the direction and extent of movement of operating parts.

Having thus disclosed my invention, what I claim as new therein and desire to secure by Letters Patent is,—

A razor sharpening machine including 25 a machine base, a shaft mounted horizontally in bearings on said base for revolution, a pair of abrasive discs fastened on said shaft spaced apart for revolution therewith, a pinion gear fastened on said shaft, a spur gear engaging 30 said pinion mounted in bearings on said base for revolution, a cam fastened flatwise to the spur gear, a frame mounted on said base for reciprocation engaging the cam being reciprocated thereby, a recumbent bar having its 35 outer end pivoted to said base for vertical oscillation and its inner end disposed between said discs, an upright hollow post being fastened to the inner end of said recumbent bar disposed between said discs, a crank pin on 40 said cam, connections from said crank pin to said hollow post oscillating said post and recumbent bar, a hollow shaft being extended through said hollow post engaged thereby for movement therewith and for independent 45 oscillation therein, a spring arm pivoted to said hollow shaft below said post being adapted to oscillate the hollow shaft and to oscillate on said pivot independently thereof, being engaged by said reciprocative frame to oscillate 50 said hollow shaft, a straight-razor blade holder being mounted in the upper end of said hollow shaft to move therewith between said discs, and means to revolve said spur gear.
